J. R. KENDRICK

TRACTOR CONTROL

Filed Feb. 14, 1923

*Inventor
James Robert Kendrick
By Frederick C. Bromley
Atty.*

UNITED STATES PATENT OFFICE.

JAMES ROBERT KENDRICK, OF ESSEX, ONTARIO, CANADA.

TRACTOR CONTROL.

Application filed February 14, 1923. Serial No. 618,926.

To all whom it may concern:

Be it known that I, JAMES ROBERT KENDRICK, a subject of the King of Great Britain, residing at the town of Essex, in the 5 Province of Ontario, in the Dominion of Canada, have invented certain new and useful Improvements in Tractor Controls, of which the following is a specification.

The invention relates to improvements in 10 tractor control as described in the present specification and illustrated in the accompanying drawing that forms part of the same.

The invention consists essentially of the 15 novel features of construction and arrangement of parts whereby the clutch lever and throttle of a tractor may be independently manipulated by a rein extending from the device.

20 This device is particularly adapted for use on a tractor providing motive power for a threshing machine, or in any instance where power is transmitted from the tractor to another instrument by means of a belt or 25 such like connection. The operator situated on the thresher, or other instrument of transmitted power, may from this point control its mechanism by use of the rein, through its connection with the clutch lever 30 and throttle of the tractor.

In the drawing, Figure 1 is a perspective view of the invention, showing the tractor clutch lever held in gear; the throttle lever being in its normal position.

35 Figure 2 is a sectional view taken on the line 1—1 of Figure 1 and illustrates more particularly the automatic releasing mechanism of the device.

Like numerals of reference indicate corresponding parts in each figure.

Referring to the drawing; 1 designates the 40 tractor clutch lever, such lever being normally manually operable; said lever controlling the communication between the motor and the transmission, and is held out of gear by a spring, which spring is not shown in the drawing as it does not constitute a part of the present invention.

50 2 is the throttle lever of the carburetor 3, which regulates the speed of the motor: a direct connection being effected with said lever in place of to the conventional manual means of operation. Though this form of connection is deemed for the purpose of this invention to be the preferred form of con-

struction; such connection may be varied to suit any special requirement.

4 is a bracket which supports the various working parts and which may be attached to the tractor in any convenient manner, said 60 bracket consisting of a metal strap having bent ends 5 and 6.

7 is a shaft rotatably supported in the bracket 4 substantially as shown. One of the projecting ends of said shaft being in the 65 form of a crank as at 8 for communicating circular motion.

9 is a rod pivotally connected at one end to the throttle lever 2 of the carburetor and the other end is constructed with a slotted piece 10 integral with or secured thereto. The end of the crank 8 slides in the slotted piece 10, thus permitting partial rotation of said shaft without imparting movement to the rod 9. Upon sufficient rotation of said 70 shaft to bring said crank end into abutment with the end 11 of the slot, further rotation thereof will impart longitudinal movement to said rod, thus actuating the throttle.

12 is a rein arm of convenient length keyed 80 upon the shaft 7 adjacent to the outer face of the end member 5 of the bracket 4. Integral with or secured to said arm is a minor arm 13.

14 is a rein secured to the arm 12 and extending therefrom for a suitable length; said rein being constructed of rope or other suitable material.

15 is a ratchet wheel rotatably mounted upon the shaft 7 adjacent to said rein arm 90 and movable in relation thereto. The said ratchet wheel is prevented from moving endwise by a collar 16 rigidly secured on the end of said shaft.

17 is a spring held ratchet affixed to the rein arm 12 and engaging the ratchet wheel teeth thus effecting simultaneous movement of said ratchet wheel with said arm 12 in the direction of the pull on said rein.

18 is an extension 18 having a pin end. 100 Integral with or secured to said ratchet wheel is an extension 18 having a pin end. This extension constitutes a crank of a given throw.

19 is a connecting rod of convenient length, one end of which is carried by the 105 pin terminus of the extension 18. The other end 20 is detachably secured to the clutch lever 1 of the tractor by means of a slot therein, thus engaging a pin extension from said clutch lever as at 21.

22 is a pawl support integral with or secured to the end 5 of the bracket 4 and being spaced parallel therewith; said support carrying a pawl 23 pivotally mounted thereon and normally held in engagement with the ratchet wheel teeth by a spring as at 24; said pawl being provided with a substantial finger terminus 25 which is formed on the side adjacent to the minor arm 13, with 10 an oblique cam plate 26, the ends of said cam plate being neatly rounded off to facilitate functioning.

27 is a slot longitudinally disposed in the arm 13 in advance of the ratchet wheel 16 teeth. Slidably mounted in said slot is a block 28 which has considerable movement therein. Interposed between the outer end of said slot and said block is a helical spring 29 which is adapted to exert a pressure on 20 said block to hold it normally to the inner end of said slot.

Projecting from the block 28 into the pathway of the cam plate 26 of the pawl is a pin 30 which is adapted upon the angular movement of the arm 13 in the direction of said pawl to engage said cam plate thereof and disengage said pawl from the ratchet wheel. Upon reverse movement of said arm 13 the pin of the block travels over 30 the reverse side of the cam plate working against the spring pressure.

31 is a comparatively large spring coiled about the axis of the rein arm 12 and is adapted to exert pressure in the opposite 35 direction to that of the pull of the rein.

In the operation of this invention the connecting arm is first attached to the clutch lever by engaging the slotted end 20 on the pin extension of the clutch lever 1. As 40 the clutch is normally out of gear the operator desiring to engage same simply pulls upon the rein 14, effecting the movement of the arm 12 which simultaneously operates the ratchet wheel 15 through the ratchet 17 45 engaging the teeth thereof. As the connecting rod 19 is attached to said clutch lever and to said ratchet wheel by means of the crank extension 18, said clutch lever is thus operated against its spring pressure 50 until it is firmly in gear. The spring actuated pawl 23 which is carried by the stationary support 22 of the bracket 4 engages the ratchet wheel teeth as it rotates, thus preventing reverse movement thereof.

55 It will be apparent that in order to adjust the throttle it is simply necessary to slacken the rein 14, which permits the arm 12 to move in the reverse direction through the spring pressure, the shaft 7 being keyed 60 to said arm 12 is actuated thereby and the crank end 8 thereof is also rotated. The crank end 8 of said shaft is permitted to slide in the slotted end piece 10 of the rod 9 for a distance equal to the angular movement 65 required to engage the clutch, where-

upon it engages the slot end 11 imparting motion to said rod which in turn actuates the throttle lever as desired.

To release the clutch it is simply necessary to retract the rein, which rotates the minor arm 13 and as said arm rotates the pin 30 is brought into engagement with the pawl cam plate 26 forcing the pawl outwardly thus releasing the ratchet wheel which through its connections releases the 75 clutch lever. When the arm 13 moves in the opposite direction again, said pin 30 travels over the other side of said cam plate of the pawl 23.

What I claim is:—

1. In a tractor control, a bracket adapted for attachment to a tractor; a shaft journaled therein having a crank end; means provided whereby the rotation of said crank end actuates the throttle lever at a predetermined point in the rotation thereof; an arm rigid with said shaft having a suitable rein extending therefrom; a ratchet wheel rotatably mounted on said shaft engaging with a ratchet carried by said arm; means detachably connecting said ratchet wheel to the tractor clutch lever and pawl means preventing recoil of said ratchet wheel.

2. In a tractor control, in combination with the tractor, a bracket, a shaft journaled therein having a crank end; a rod extending from the throttle lever to said crank end, said rod having a slotted end in which said crank end slides; an arm rigid with said shaft having a suitable rein extending therefrom; a ratchet wheel rotatably mounted on said shaft engaging with a ratchet carried by said arm; means detachably connecting said ratchet wheel to the tractor clutch lever and pawl means preventing recoil of said ratchet wheel.

3. In a tractor control, in combination with the tractor, a bracket, a shaft journaled therein having a crank end; means provided upon the rotation of said crank end to actuate the throttle lever at a predetermined point in the rotation thereof; an arm rigid with said shaft having a suitable flexible rein extending therefrom, a ratchet wheel rotatably mounted on said shaft having engagement with a ratchet carried by said arm, a pin extension from said ratchet wheel, a connecting rod carried by said pin extension detachably engaging the clutch lever, and pawl means preventing recoil of said ratchet wheel.

4. In a tractor control, in combination with the tractor, a bracket, a shaft journaled in said bracket having a crank end, means provided whereby the rotation of said crank end actuates the throttle lever at a predetermined point in the rotation thereof; an arm rigid with said shaft having a suitable flexible rein extending therefrom;

a ratchet wheel rotatably mounted on said shaft engaging with a ratchet carried by said arm, means detachably connecting said ratchet wheel to the clutch lever, a spring held pawl supported from said bracket and engaging said ratchet wheel; a spring held block slidable in an arm other than the aforesaid arm and having a rigid pin adapted upon rotation to engage a lateral

pawl cam face to effect disengagement 10 thereof.

Signed at Essex, Ontario, Canada, this fifth day of February, 1923.

JAMES ROBERT KENDRICK.
